UNITED STATES PATENT OFFICE.

JOHN C. BANNISTER, OF KEWANEE, ILLINOIS.

METHOD OF AND APPARATUS FOR MAKING SAND MOLDS

1,034,334.

Specification of Letters Patent.

Patented July 30, 1912.

Application filed November 8, 1911. Serial No. 659,159.

To all whom it may concern:

Be it known that I, JOHN C. BANNISTER, a citizen of the United States of America, residing at Kewanee, in the county of Henry 5 and State of Illinois, have invented a new and useful Method of and Apparatus for Making Sand Molds, of which the following is a specification.

My invention relates to the forming of 10 sand molds which are later filled with molten metal in manufacturing castings, and more particularly relates to a method of simultaneously making a plurality or series of green sand molds in multiple which 15 are afterward filled simultaneously with molten metal to produce a number of castings, such as for example, pipe fittings and similar materials.

One object of my invention is to provide 20 a novel method of making green sand molds, in which the mold, and cores, are simultaneously formed, the time required to form the molds is lessened, the number of necessary assembling operations is reduced, and 25 the cost of preparing the molds in readiness for the casting operation is materially lowered.

Another object of the invention is to provide an improved method of making green 30 sand molds in multiple whereby a series of such molds including, when cores are used, cores therefor formed of green sand are simultaneously formed and assembled in readiness for a later casting operation, 35 whereby the mold forming operations are facilitated and the use of green sand cores is made possible.

A further object of this invention is to provide molding apparatus having novel 40 means for making sand molds and green sand cores either singly or in multiple in accordance with my improved method forming part of this invention.

Referring to the drawings forming part 45 of this specification, Figure 1 is a longitudinal sectional elevation, the section being taken on the line I—I of Fig. 2, showing apparatus constructed and arranged for use in connection with a pneumatic molding 50 machine, in simultaneously forming the cores and constructing the molds for a plurality of castings in accordance with my improved method the particular casting illustrated being in the form of pipe fittings

known as T's. Fig. 2 is a sectional plan of 55 the apparatus shown in Fig. 1, the section being taken on the line II—II of Fig. 1. Fig. 3 is a sectional end elevation of the apparatus shown in the preceding figures, the section being taken on the line III—III of 60 Fig. 2. Fig. 4 is a sectional end elevation similar to that shown in Fig. 3 showing a modified form of apparatus constructed and arranged for use in carrying out my improved method.

For the sake of clearness the sand is not shown in the sand boot, flask and cores, the apparatus being shown as assembled in readiness to supply sand from the boot to the mold.

In the drawings, referring to Figs. 1, 2 and 3, the numeral 2 designates a sand boot, such as forms part of and is used in connection with the Hewlett molding machine, employing compressed air or air under pressure for delivering the sand into the flask of the mold, and 3 is a modified form of bottom plate removably secured to and forming part of the sand boot 2, as constructed in accordance with this invention. A pattern plate, which is split or divided lengthwise into a top section 4 and a bottom section 5, is employed in the mold forming operation in connection with the sections 6 and 7 of the flask, in which the cope and 75 drag molds are formed. The flask, which may be of any known construction, is provided with the usual dowel pins 8 by which the flask sections are assembled or booked and are maintained in registering position. 80 The sections 4 and 5 of the pattern plate are provided with holes 9 in the ears 10 thereon which register with and are engaged by the dowel pins 8 in positioning the pattern plate and half patterns thereon with respect to 85 the flask sections. Each of the pattern plate sections 4 and 5 is provided with a series of half patterns 11, the half patterns on one section 4 registering with those on the other section 5 when booked or assembled. The contacting or adjacent faces of the pattern plate sections 4 and 5 have cavities or recesses 90 therein which when the pattern plate sections are assembled form sectional core boxes 12 in which the green sand cores are 105 built up and formed in carrying out the steps of my improved method. The opposite depressions or recesses forming the core-

boxes 12 are necessarily positioned with respect to the half patterns 11, so that each of the series of core-boxes 12 is in registering position relative to its co-acting half patterns 11 on the pattern plate sections 4 and 5. The longitudinal axial centers of the core-boxes in one face of the pattern plate sections are out of line with or eccentric to the corresponding center on each half pattern on the opposite faces thereof a distance equal to the thickness of the section of the pattern plate to which the half patterns 11 are secured. By so constructing the half patterns with reference to the recesses forming the core-boxes, cores formed in the core-boxes will be in axial alinement with the molds formed in the cope and drag molds by the half patterns 11 when the cores have been transferred from the pattern plate into the mold and the pattern plate has been removed, and the cope and drag molds are assembled in position and in readiness for the casting operation. The bottom-plate 3 on the sand boot 2 is provided with a series of transversely extending openings or holes and in part of these holes drop tubes or blow plugs 13 and 14 are secured by one end which extend downwardly from the under surface of the bottom-plate 3. The drop tubes 13 and 14 have closed lower ends and the tubes 13, 14 have side openings 13^a, 14^a adjacent to their lower end, which are located and arranged to be substantially in alinement with the axial center of the recesses or cavities forming the core-boxes in the pattern plate when the apparatus is assembled in position to form the mold. The pattern plate sections 4 and 5 have openings 15 therethrough which are located in the pattern plate so as to position one of the openings in line with the end of each of the core-box cavities and in line with the end of any cavities forming branches in the core-boxes. The drop tubes 13 which extend into the openings 15, have a single opening 13^a through the side wall adjacent to the closed lower end thereof and the drop tubes 14 have double openings 14^a, 14^a through the side wall on opposite sides of the axial center of these tubes and adjacent to the lower closed end of the tubes. The bottom-plate 3 on the sand boot 2 also has a series of openings in which drop tubes 16 are secured having closed lower ends and a single opening 16^a through the side wall located adjacent to the closed lower ends thereof. The tubes 16 which are somewhat longer than the drop tubes 13 and 14 also extend downwardly through registering openings 17 in the pattern plate sections 4 and 5 and serve to supply sand to the lower section of the flask in forming the drag of the mold in the construction shown in Figs. 1, 2 and 3. A series of openings 18 are provided at intervals in the bottom plate 3 through

which sand is supplied to the top section of the flask in forming the mold in this section.

In the modified form of apparatus shown in Fig. 4 the drop tubes or blow plugs 16 extending from the bottom plate 3 of the boot 2 through openings in the pattern plate into the bottom section of the flask are omitted and a second sand boot 2' is employed which delivers sand upwardly to the flask section in forming the mold. In this construction the flask sections and the pattern plates forming the molds are booked in the same manner as in Figs. 1, 2 and 3 and are then placed between the bottom plates of the opposite sand boots, one boot 2' supplying sand to form the mold in the top section of the flask and the other boot 2' to form the mold in the bottom section through transverse openings 18' provided in its bottom plate 3' for that purpose.

The method of supplying sand through the medium of an air blast or fluid under pressure to a flask by lifting or forcing the sand upwardly through a sand boot as shown in Fig. 4 herein by which packing and forming channels in the sand contained in the boot is avoided and overcome, forms the subject matter of my co-pending application Serial No. 659,160, filed November 8, 1911, for a method of and apparatus for forming sand molds.

Blow plugs 13' and 14' are provided in the construction of Fig. 4 which are located in spaced apart relation to each other and to the ends of the series of core-boxes 12' formed in the pattern plate sections 4' and 5' shown in Fig. 2, in the same manner as in Figs. 1 and 3, these blow plugs extending downwardly into proximity to the ends of the cavities forming the core-boxes in the pattern plate in which the cores for the fittings being made are formed in the same manner as before described. It should be noted that in all of the drop tubes or blow plugs the outer ends are closed and the openings 13^a, 14^a and 16^a adjacent to the outer ends thereof are in the sides of the drop tubes or blow plugs so that in this construction also the sand delivered through the drop tubes or blow plugs is caused to emerge therefrom into the core-boxes in lines parallel with the horizontal centers of the cores. The blow plugs 14 and 14' which extend between the adjacent ends of the adjoining core cavities are provided with two openings, 14^a, 14^a, each opening supplying sand to an end of such core cavities and each face on these plugs determining the length of the cores formed.

In carrying out my improved method of molding, the top and bottom sections 4 and 5 of the pattern plate are assembled and the pattern plate and sections of the flask are booked together, as shown in the drawings.

In the construction shown in Figs. 1, 2 and 3 the booked or assembled flask and pattern plate are brought into position with the bottom plate 3 on the sand boot 2 of a Hewlett 5 molding machine. Air under pressure is admitted to the sand boot and the sand is thereby caused to pass into the flask and into the cavities or recesses forming the core-boxes through the series of drop tubes or 10 blow plugs, 13, 14, 16 and the openings or holes 18 so as to fill the flask and core-boxes with sand. The sprue is provided in the usual manner during the flask filling operations. By reason of the closed outer 15 ends of and the provision of the side outlets or openings in the blow plugs, the direction of flow of the sand is changed while still within the blow plugs and the sand is caused to flow from the blow plugs into the 20 core-boxes in paths parallel with the longitudinal axes of the cores, and being caused to travel from the opposite sides of the flask toward the center thereof, the sand is caused to distribute evenly and is uniformly compacted within the flask and core-boxes so 25 as to form sand cores and molds having uniform density. The sand boot 2 and mold are then separated. The top section of the flask is then lifted from the pattern plate 30 and the top section 4 of the pattern plate removed so as to uncover the formed cores. The removed flask section is then again placed in position on the bottom half of the pattern plate, which still remains in position, the dowel pins on the flask insuring 35 the parts being replaced in registering position. The flask is then turned or rolled over, so as to bring the drag mold uppermost. The then uppermost flask section is lifted 40 from the bottom section 5 of the pattern plate which is still in position between the flask sections. This bottom section 5 of the pattern plate is then removed from the cope or then lower flask section and the top section 45 is replaced in position, resting on the drag and bringing the cope and drag molds into registering position with each other, with the axis of each recess or cavity therein in alignment with the axes of its core. 50 When the then uppermost section and top section 4 of the pattern plate are first removed, the cores remain in position in the bottom section of the pattern and by replacing the top flask section in position on the bottom half of the pattern plate the cores 55 are all simultaneously and accurately placed in position in the mold formed in the top flask section so that when the assembled mold is later turned over, the cores are in 60 the position in the half mold which they are to occupy during the casting operation. When the other section of the pattern plate is then later removed after the mold turning operation and the then uppermost flask section 65 is again placed in position on the bot-

tom section, the parts of the mold including the cope, the drag and the cores will then be assembled in registering position in readiness for the casting operation.

With the apparatus shown in Fig. 4 the 70 method of forming the molds and cores is the same as before described with the exception that, instead of supplying sand to the drag mold from the top boot 2' on top of the cope through the blow plugs 16, a second sand boot 2' is employed to supply sand 75 through openings 18' in the bottom plate 3' therefor to the drag, in addition to the other boot 2', which supplied the sand to the cope through holes 18' in its bottom plate 3' and 80 to the core-boxes through the blow plugs 13' and 14'.

A series of openings will be left in the completed sand molds in the cope and drag by the drop tubes or blow plugs for supplying sand to the apparatus, but the wall of sand formed between any such openings and an adjoining opening will be of sufficient thickness to prevent breaking out during the casting operation. The series of openings left by the blow plugs for supplying sand to the core-boxes also will remain in the completed mold, but as the ends of the cores shut off these openings from the cavities or recesses of the mold, later filled with molten metal, the forming of clean castings is insured. 85 90 95

The advantages of my invention will be apparent to those skilled in the art. By the use of my improved method a series of 10 molds are made in multiple and the cores for such molds are formed simultaneously therewith. Green sand cores are molded in place in multiple and the necessity of transferring the cores singly and by hand into the molds 10 is avoided and overcome.

I am the first to devise a method of molding and making green sand molds in multiple in which the cope, drag and the cores therefor, when cores are used, are simultaneously formed and in which a plurality or series of molds are simultaneously formed, and I intend to cover such construction broadly in the claims. 11

Modifications may be made in the construction and arrangement of the parts forming the apparatus used in carrying out my improved method. The drop tubes or blow plugs for supplying sand to the core-boxes may be located on the bottom plate of either of the two sand boots employed in the construction shown in Fig. 4. The blow plugs may be entirely omitted, except for the purpose of supplying sand to the core-box cavities. The blow plugs may be used with one or both of the sand boots when desired. 1 1

My improved method may be employed when desired in making the cope and drag molds and the core or cores for a single cast- 1

ing which may be large or small and other variations in the construction and arrangement of the parts forming the apparatus may be made within the scope of my invention as defined in the appended claims.

I claim:-

1. The method of making sand molds consisting in assembling a pattern plate between flask sections wherein the cope and drag molds are formed, then causing sand to be delivered through the open ends of the flask sections into the flask sections to thereby simultaneously form the cope and drag molds therein, then removing the pattern plate from between the flask sections and assembling the so-formed cope and drag molds.
2. The method of making sand molds in multiple consisting in assembling a pattern plate having a plurality of patterns thereon between flask sections wherein the cope and drag molds are formed, then causing sand to be delivered through the open ends of the flask sections into the flask sections to thereby simultaneously form the multiple molds therein, then removing the pattern plate from between the flask sections and assembling the so-called cope and drag molds.
3. The method of making sand molds consisting in assembling a sectional pattern plate having core forming cavities therein between flask sections wherein the cope and drag molds are formed, then causing sand to be delivered through the open ends of the flask sections into the flask sections and core forming cavities to thereby simultaneously form the cope and drag molds and the core therefor, then removing the sectional pattern plate from between the flask sections and assembling the so-formed cope and drag molds with the core in position therebetween.
4. The method of making sand molds in multiple consisting in assembling a sectional pattern plate having a plurality of patterns thereon and core forming cavities therein between flask sections wherein the cope and drag molds are formed, then causing sand to be delivered through the open ends of the flask sections into the flask sections and the core forming cavities to thereby simultaneously form the multiple molds and cores therefor, then removing the sectional pattern plate from between the flask sections and assembling the so-formed cope and drag molds with the cores in position therebetween.
5. The method of making sand molds consisting in assembling a sectional pattern plate having core forming cavities therein between flask sections wherein the cope and drag molds are formed, then causing sand to be delivered through the open ends of the flask sections into the flask sections and core forming cavities to thereby simultaneously form the cope and drag mold; and the core

therefor and causing the sand to enter the core forming cavities in lines substantially parallel to the longitudinal axes of the cores formed therein, then removing the sectional pattern plate from between the flask sections and assembling the so-formed cope and drag molds with the core in position therebetween.

6. The method of making sand molds in multiple consisting in assembling a sectional pattern plate having a plurality of patterns thereon and core forming cavities therein between flask sections wherein the cope and drag molds are formed, then causing sand to be delivered through the open ends of the flask sections into the flask sections and the core forming cavities to thereby simultaneously form therein the multiple molds and cores therefor and causing the sand to enter the core forming cavities in lines substantially parallel to the longitudinal axes of the cores formed therein, then removing the sectional pattern plate from between the flask sections and assembling the so-formed cope and drag molds with the cores in position therebetween.

7. Apparatus for making sand molds comprising flask sections in which the cope and drag molds are formed, pattern plates between the flask sections having opposite half-patterns on the outer faces thereof, sand-boots engaging with the open sides of the flask sections having means for discharging sand therefrom, and means on said sand-boots arranged to deliver the sand discharged therefrom simultaneously into the flask sections on opposite sides of the pattern plates during the mold forming operations.

8. Apparatus for making sand molds comprising flask sections in which the cope and drag molds are formed, sectional pattern plates between the flask sections having half-patterns on opposite faces and registering core-forming cavities in the adjacent faces thereof, sand-boots on the open top of the upper flask section having means for discharging sand therefrom, and means on said sand boots arranged to deliver the discharged sand simultaneously into the flask sections on opposite sides of the pattern plate and the core-forming cavities in the adjacent faces of said plates during the mold forming operations.

9. Apparatus for making sand molds in multiple comprising flask sections in which the multiple molds are formed, a sectional pattern plate between the flask sections having a plurality of half-patterns on opposite faces and registering core-forming cavities in the adjacent faces of said plate, a sand boot on the open top of the upper flask section having means for discharging sand therefrom, and means on the sand boot arranged to deliver the discharged sand simul-

- 5 taneously into the flask sections on opposite sides of the pattern plate and the core-forming cavities in adjacent faces of said pattern plate during the mold forming operation.
- 10 5. 10. Apparatus for making sand molds comprising flask sections in which the cope and drag molds are formed, a sectional pattern plate between the flask sections having a half-pattern on opposite faces and registering core forming cavities in the adjacent faces thereof, a sand boot on the open top of the upper flask section having means for discharging sand therefrom, and means on said sand boot arranged to deliver the discharged sand simultaneously into the flask sections on opposite sides of the pattern plate and the core forming cavities in the adjacent faces of said plate during the mold forming operations, said means being adapted to deliver the sand into the core forming cavities in lines substantially parallel to the longitudinal axis of the core formed therein.
- 15 11. Apparatus for making sand molds in multiple comprising flask sections in which the multiple molds are formed, a sectional pattern plate between the flask sections having a plurality of half-patterns on opposite faces and registering core-forming cavities in the adjacent faces of said plate, a sand boot on the open top of the upper flask section having means for discharging sand therefrom, and means on the sand boot ar-
- 20 ranged to deliver the discharged sand simultaneously into the flask sections on opposite sides of the pattern plate and the core forming cavities in adjacent faces of said pattern plate during the mold forming operation, said means being adapted to deliver the sand into the core-forming cavities in lines substantially parallel to the longitudinal axes 40 of the cores formed therein.
- 25 12. In apparatus for making sand molds a blow plug or drop tube through which sand is delivered into the molds, said tube having a closed outer end and a side outlet 45 adjacent to said closed outer end whereby the direction of flow of sand passed through the blow plug is changed in emerging from the blow plug.
- 30 13. In apparatus for making sand molds a blow plug or drop tube through which sand is delivered into the molds, said tube having a closed outer end and side outlets 50 adjacent to said closed outer end whereby the direction of flow of sand passing through the blow plug is changed in emerging from the blow plug.
- 35 In testimony whereof, I have hereunto set my hand.
- JOHN C. BANNISTER.
